LOOSE LEAF BINDER

Application filed February 8, 1930. Serial No. 426,871.

This invention relates to loose leaf binders and it has particular reference to a binder provided with means for simultaneously releasing a plurality of leaf fasteners.

8 It has heretofore been proposed to form a loose leaf binder with a plurality of fastening devices which could be individually and separately secured to or released from members adapted to secure a number of leaves contained in the binder. The present invention provides means whereby several fastening members may be operated at one time, and, more specifically, the invention contemplates the provision of means whereby the 15 fastening devices on both sides of a group of leaves may be concurrently operated and will release the leaf-securing members at either of their ends without, at the same time, releasing their other ends.

20 As hereinafter more fully explained, the objects of the invention may be attained by providing a binder or cover with a plurality of fasteners disposed within the cover, which may be interlocked with prongs passing through the leaves by a rod or bar extending longitudinally of the cover, and which, when moved in one direction, releases the fastening devices on one side from the corresponding prongs, effects a similar release for 25 the prongs on the other side when moved in the opposite direction, and, when maintained in an intermediate position, secures the fastening devices and prongs on both sides of the stack of leaves. This embodiment of the 30 invention, which permits of increased ease of assembly or removal of leaves from the stack, is illustrated in the accompanying drawings, wherein:

35 Fig. 1 is a view in perspective of an open binder containing a plurality of leaves locked therein;

40 Fig. 2 is a view in perspective of an open binder with the fastening means disengaged from one side of the leaf stack;

45 Fig. 3 is a view in perspective of the fastening means detached from the binder;

50 Fig. 4 is a view in perspective of the leaf-impaling means;

55 Fig. 5 is a vertical transverse cross-sectional

view through the closed book in line with one of the leaf posts; and

Fig. 6 is a plan view of a fastening device showing the arrangement of the post-engaging slots.

60 The binder comprises a pair of cover members 10 and 11 hingedly connected to a back 12, to form a cover adapted to retain a pile of leaves 13 securely, but in such manner that they may be freely removed, replaced, or rearranged. A series of marginal perforations in the leaves 13 is adapted to receive leaf-impaling means, shown in detail in Fig. 4, comprising a pair of opposed transfer bars 14 and 15, each having associated therewith 65 a series of leaf posts 16. The leaf posts 16 are fixedly disposed in apertures provided in the bars 14 and 15 and have reduced portions 18 protruding from the opposite side of the bars. The free ends of the leaf posts 16 are provided with reduced portions 19 adapted to be received by registering apertures 20 70 provided in the complementary transfer bar.

75 The transfer bars 14 and 15 are arranged on opposite sides of the pile of leaves 13 with the leaf posts 16 disposed in the perforations thereof and with the reduced portion 19 of each leaf post extending through the aperture 20 in the opposed transfer bar. The reduced portions 18 and 19 are thus aligned 80 on the outside of each transfer bar 14 or 15, (Fig. 2) and are each provided with an annular groove 22 adapted to be engaged by a fastening device which will presently be described.

85 A piece of cloth 23 is glued or otherwise secured across the entire inner face of the back 12, and is provided with transversely overhanging marginal portions 24, each of which is folded and stitched to form a sheath 90 for receiving an elongated clamping bar 25. The clamping bar 25 is provided with a plurality of apertures 26 adapted to register with the reduced portions 18 and 19 of the leaf posts 16. The marginal portions 24 of the cloth 23 are removed in the region of each pair of apertures 26 to accommodate a fastener or locking plate 27, slidably mounted upon the clamping bars 25 by flanges 28 and 29 formed thereon at its opposite edges. 100

These members are positioned on the bars 25 before the cloth 23 is stitched thereto. The flange 29 on one side of each of the locking plates 27 is formed only in the central portion, thus leaving the outer portions of this edge of the plate free for forming bearings 31 and 32, by curling the edge of the plate 27. A pivot pin 33 is supported in the bearings 31 and 32 thus formed and at its central portion engages with a similarly formed bearing 34 provided on either edge of a connecting plate 35. Each connecting plate 35 serves as a spacing and connecting means for a pair of complementary locking plates 27 and together therewith forms a fastening unit.

An actuating member or shifting bar 36 is secured at various points along its length to the connecting plates 35 of the fastening units (which in the present instance are two in number). A lug 37 formed at each end of the shifting bar 36 provides a means for grasping the bar to simultaneously shift in either direction the longitudinal positions of all of the locking plates 28. The position of the bar is so related with the remaining elements that movement in one direction permits of the release of the fasteners 27 on one side of the stack of leaves 13, while movement in the opposite direction from a vertical position, permits of the release of the fasteners on the opposite side of the leaves.

As shown in Fig. 6, each of the locking plates 27 is provided with a pair of elongated apertures 41 and 42 adapted to cooperate with the reduced portions 18 and 19 of the posts 16. Each aperture 41 is formed with a slot 43 of a width designed to cooperate with the groove 22 of the reduced portion 18 or 19, and with an enlargement 44 at one end of the slot to permit entrance or removal of the reduced portion from the aperture when the parts are in proper longitudinal relation. The apertures 42 have groove-engaging slots 45 similar to the slots 43 of the apertures 41 but they are provided with enlargements 46 at each end of their groove-engaging slots.

From the foregoing, it will be evident that when the locking plates 27 are so adjusted longitudinally, that all of the reduced portions 18 and 19 are disposed midway of the apertures 41 and 42, as shown in Fig. 1, the leaves are locked securely between the transfer bars 14 and 15. When, however, it becomes necessary to change a sheet or to change the position of a sheet, the alteration may be effected by pushing the lower lug 37 of the shifting bar 36 inwardly (upwardly as viewed in Fig. 6). This places the apertures in the locking plate 27 shown on the left-hand side of Fig. 6 in such a position that this plate and all similar locking plates 27 on the same side of the binder may be lifted from engagement with the reduced portions 18 and 19 and

dropped into the position shown in Fig. 2. The same operation places the apertures in the right-hand locking plate 27 in position so that, while the reduced portion 18 of the bar 15 is held in locked relation with the aperture 41, the reduced portion 19 of the bar 14 is in registry with one of the enlarged portions 44 of the aperture 42, thereby permitting the bar 14 and its associated posts 16 to be lifted from the pile of leaves 13. If it is desired to effect the change of leaves at some point between the top and bottom of the stack, all of the leaves above the point where the change is to be made may be removed with the bar 14. By so doing, the removed sheets may be held in correct alignment by the leaf posts 16 on the bar 14 while the change is being made.

If the leaf to which access is desired happens to be closer to the bottom of the stack, or if the book happens to be lying so that what has been considered the top cover of the book is the lower cover, the operation may be performed as described or by moving the bar 36 outwardly instead of inwardly, referring, of course, to the bottom end of the bar or the end closest the operator. This operation releases the plate 15 instead of the plate 14.

From the foregoing it will be seen that a simple, practical means for readily changing the leaves in binders of this type has been provided, and while a detailed embodiment has been described, it is understood that numerous changes in size, shape and arrangement of parts may be made without departing from the spirit and scope of the invention as defined in the appended claims.

What is claimed is:

1. A loose leaf binder having a pair of transfer members, locking means associated therewith, and single means for selectively releasing either of said transfer members.

2. A loose leaf binder, having a plurality of leaf-retaining posts and means for simultaneously engaging or releasing predetermined groups of said posts to permit access to the leaves retained thereby.

3. In a loose leaf binder having a pair of opposed cover members, a bar member mounted on each cover member, each bar member being formed with apertures, a fastening unit extending between the cover members and slidably mounted on each of the bar members, a pair of impaling bars for securing a plurality of superimposed leaves between the cover members, protuberances on each bar, all of said protuberances being received in the apertures of the bar member and also being engaged by and locked in the fastening unit, said fastening unit being slideable to two selective positions to disengage the protuberances on either impaling bar.

4. In a loose leaf binder having a pair of opposed cover members, a bar member mounted on each cover member, each bar member

being formed with apertures, a fastener slidably mounted on each bar member, said fasteners arranged in opposed relation, connecting means extending between the fasteners and having a hinge connection with each of the fasteners, a pair of impaling bars for securing a plurality of superimposed leaves between the cover members, a protuberance on each extremity of each bar, said protuberances being received in the apertures of the bar member and also being engaged and locked in the fasteners, said fasteners and connecting means being movable as a unit to two selective positions to disengage the protuberances on either impaling bar.

5. In a loose leaf binder adapted to contain a plurality of apertured leaves, a series of leaf posts disposed in the apertures of the leaves and extending therethrough, spaced means in the binder for receiving the opposite ends of said posts, and a fastener unit movably mounted on said means and normally releasably engaging the post ends, said fastener unit being selectively movable to simultaneously disengage either of the common series of ends of said posts.

6. A loose leaf binder comprising a pair of cover members, a back connecting said cover members for hinging movement, a pair of impaling bars for securing a plurality of leaves between said cover members, protuberances on each of said impaling bars, a longitudinally extending bar mounted on each cover member adjacent said back and each formed with apertures for receiving the protuberances on the impaling bars, a plurality of fasteners slidably mounted on each longitudinally extending bar for locking engagement with the protuberances of the impaling bars, a plurality of connecting plates extending between the opposite longitudinal bars, each connecting plate pivotally connected to each of a complementary pair of fasteners on opposite longitudinal bars, and an actuating member secured to all of said plates and operable to simultaneously move said plates and attached fasteners, said fasteners when moved to one position being formed to release the protuberances of one impaling bar and when moved to a second position being formed to release the protuberances of the other impaling bar.

7. A loose leaf binder comprising a pair of cover members, a back connecting said cover members for hinging movement, a pair of impaling bars for securing a plurality of leaves between said cover members, grooved studs on each of said impaling bars, a longitudinally extending bar mounted on each cover member adjacent said back and each formed with apertures for receiving the studs of an impaling bar, a plurality of fasteners slidably mounted on each of the longitudinal bars and each formed with an aperture for

receiving a stud in locking engagement with the groove thereof, a plurality of connecting plates extending between the opposite longitudinal bars, each connecting plate pivotally connected to each of a complementary pair of fasteners on opposite longitudinal bars, and an actuating member secured to all of said plates and adapted to be actuated to simultaneously move all of said plates and attached fasteners, said fasteners when moved to one position being formed to release all of the studs of one impaling bar, and when moved to a second position being formed to release the studs of the other impaling bar.

8. In a loose leaf binder having a pair of opposed cover members, spaced bar means on the binder, a pair of impaling bars for securing a plurality of superimposed leaves, cooperating interengaging means on the impaling bars and the bar means, a fastening unit extending between the cover members and movably mounted on the bar members, said unit normally retaining the cooperating means on the impaling bars and bar means in interengaged relation, said unit being movable to two selective positions to release either impaling bar for disengagement from the bar means.
